CLAIM

The ornamental design for a small pet door, as shown and described.

DESCRIPTION

The present invention relates to a small pet door. The frames are joined together sandwiching a house door.

FIG. 1 is a perspective view from a first side of the pet door of the present invention;

FIG. 2 is a perspective view from a second side opposite the first side of the pet door of the present invention;

FIG. 3 is a front view of the first frame member of the pet door of the present invention, the outer member disclosed in FIG. 1 has been eliminated for ease of illustration;

FIG. 4 is a rear view of the first frame member of the pet door of the present invention;

FIG. 5 is a perspective view of the first frame member of the pet door of the present invention;

FIG. 6 is a front view of the second frame member of the pet door of the present invention, the first frame member in FIG. 3 has been eliminated for ease of illustration;

FIG. 7 is a rear view of the second frame member of the pet door of the present invention; and,

FIG. 8 is a perspective view of the second frame member of the pet door of the present invention.
